BUILT-UP SHOE

Joseph Burger, New York, N. Y.

Application March 6, 1939, Serial No. 259,999

1 Claim. (Cl. 36—71)

This invention relates to improvements in shoes for men and women and consists of a novel addition and arrangement embodied in the construction of shoes of regular or conventional types to be worn by normal feet, the principal purpose of which is to have the wearer of these shoes appear taller.

Devices of this character as hitherto utilized in conventional types of shoes consisted essentially of a readily insertable and removable insert commonly referred to as an elevator which is placed within each shoe and which is so constructed as to elevate the heel and arch of the foot and to support the same above the normal inner sole surface of the shoe. Such devices have not proved satisfactory in use as no means were provided in their construction to prevent shifting of the same within the shoe as they were not made to extend past the toes of the foot, they caused numerous foot disorders due to the unnatural distribution of weight between the heel, ball and toes of the foot, further cramping the foot within the shoe and also resulting in forcing the shoe out of shape thus permanently distorting the same. These devices furthermore after a short interval of use become in themselves distorted due to the action of perspiration thereon as well as by the movement and pressure of the foot causing their shifting action.

The object of this invention is to obviate the above mentioned as well as other known disadvantages by providing an elevator device which is made across standard sized lasts with a high shank elevation for use with conventional shoes worn by normal feet that will give an apparent increase in height to the wearer and yet afford perfect comfort in a well fitting shoe, the elevator being so designed as to completely cover the entire inner sole surface of the shoe, and to be readily insertable and removable from the shoe.

A further object of this invention relates to the provision of a fore pocket part constructed as an integral part of the shoe the purpose of which is to hold the elevator securely in position when placed in the shoe and at the same time permit ready removal thereof.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein—

Figure 1 is a vertical longitudinal sectional view through a shoe showing the application of the invention.

Figure 2 is a sectional view taken on line 2—2 of Figure 1.

Figure 3 is a vertical transverse sectional view through the front part of the shoe taken on line 3—3, Figure 1.

Figure 4 is a vertical transverse sectional view through the heel part of the shoe taken on line 4—4, Figure 1.

Referring to the drawing, 10 denotes a conventional form of shoe made in the manner well known and comprising an outer sole 11, heel 12, counter 13, box-toe 14, inner sole 15 and welt 16. Inasmuch as the shoe proper constitutes no part of the invention a detailed description thereof and the manner of making the same is deemed unnecessary.

Provided in superposed relation to the inner sole 15 of the shoe 10 is a built-up elevator 18 which comprises a fixed fore-pocket 19 and a removable elevator insert 20 and molded inner sole 21. The fore pocket part 19 is preferably formed of a soft leather or any other suitable material, the side and front edges of which are turned under and stitched as at 22 to the innersole of the shoe to define with relation to the inner sole 15 a pocket of substantially tapering width from the open edge 23 thereof to its closed end 24 adjacent the box toe 14. The length of the fore-pocket part 19 is such as to extend for substantially the full length of the sole engaging portion of the shoe as clearly shown in Figures 1 and 2. Overlapping the free edge portion 23 of the fore part pocket 19 and secured thereto in any desired manner is a flap 25 of any suitable material such as leather or fabric, constituting a sock lining which is so shaped as to snugly fit the contour of the shoe and inner sole 15, this flap being adapted to be raised to permit the placement of elevator insert 20 and molded inner sole 21 within the fore pocket part 19.

The elevator insert 20 is preferably made of cork or any other resilient material having a contour corresponding to that of the inner sole 15 and of a tapering thickness from the heel portion thereof to the front or toe portion abutting the closed end 24 of the pocket 19. That portion of the elevator insert 20 constituting the heel supporting portion is of uniform thickness and comprises the thickest part of the insert.

The shape and size of the elevator insert is such as to snugly fit both within the fore pocket part 19 and the side wall surfaces of the shoe in the manner clearly shown.

5 Superposed over the elevator insert 20 is a molded inner sole 21 preferably formed of leather having the same contour as the elevator insert 20, the molded inner sole 21 being preferably made comparatively thin and of substantially uniform 10 thickness, and functioning to reinforce and protect the cork elevator insert 20.

In use, by first raising the flap or sock lining 25, both the cork elevator insert 20 and molded inner sole 21 are inserted into the fore pocket 15 part 19 which thereby acts to retain the same in fixed relation to the shoe 10, the flap 25 being then lowered so as to rest on top of the molded inner sole 21. It will be seen that neither pressure of the foot nor the effect of perspiration can 20 cause any distortion, shriveling or wrinkling, or any movement of the elevator parts to affect the satisfactory use thereof.

The advantages of the built up fore pocket part are as follows: It holds the elevator insert 20 and molded inner sole 21 in position as part of 25 the shoe and at the same time permits ready removal thereof; avoids tightening up on the shoe size caused by the shriveling and curling due to the perspiration of the wearer's foot in 30 that this curling up tends to reduce the room in the fore part of the shoe; allows the applicability of a metatarsal pad or other similar device to be concealed beneath this built up fore pocket part; and permits the cork elevator insert and molded 35 inner sole to be removed for the necessity of repairing the shoe without the chance of destroying

or damaging the cork elevator insert and molded inner sole.

It is to be understood that no parallel or comparison exists or is to be drawn between this invention and the so-called "extension shoe" 5 worn by cripples. The elevator device embodying this invention is to be worn bilaterally by people with normal feet, while the "extension shoe" is worn unilaterally by cripples who wear a regular shoe on the normal foot as a mate to the "extension shoe." 10

Having thus described my invention, I claim as new and desire to secure by Letters Patent:

In a shoe, elevator means for increasing the apparent height of a person comprising a removable resilient elevator insert shaped to snugly fit within said shoe and covering the entire foot supporting surface thereof, a fore pocket part including a permanent fixed part of the shoe arranged over the sole portion of said supporting 20 surface and defining therewith the pocket for receiving the corresponding part of the elevator insert, said fore pocket being formed of soft material having inturned edges secured to the upper and inner sole of said shoe and extending from 25 side to side of said shoe and from the front of said shoe to a line transversely of the shank portion thereof thus providing a pocket with a free edge portion, a flap having an edge thereof secured in overlapping relation to the free edge 30 portion of said fore pocket part, said elevator insert being formed of cork of maximum thickness along the heel portion thereof and gradually tapering thickness along the arch, sole and toe portions thereof.

JOSEPH BURGER.
